(57) **CLAIM**

The ornamental design for a scrub top, as shown and described.

DESCRIPTION

FIG. 1 is a front view of a scrub top showing the claimed design;

FIG. 2 is a rear view thereof;

FIG. 3 is a left side view thereof;

FIG. 4 is a right side view thereof;

FIG. 5 is a front perspective view thereof;

FIG. 6 is a top view thereof; and,

FIG. 7 is a bottom view thereof.

The dot-dash broken lines in the figures and the areas within the dot-dash broken lines show portions of the scrub top that form no part of the claimed design.

The dashed broken lines show a stitching pattern. The dashed broken lines form part of the claimed design.
